CLAIM

The ornamental design for a lunch kit, as shown and described.

DESCRIPTION

FIG. 1 is a top perspective view of a lunch kit;
FIG. 2 is a front view of the lunch kit illustrated in FIG. 1;
FIG. 3 is a right side view of the lunch kit illustrated in FIG. 1;
FIG. 4 is left view of the lunch kit illustrated in FIG. 1;
FIG. 5 is a back side view of the lunch kit illustrated in FIG. 1;
FIG. 6 is a top view of the lunch kit illustrated in FIG. 1; and,
FIG. 7 is a bottom view of the lunch kit illustrated in FIG. 1.
The broken lines and areas within in FIG. 7 depict portions
of the lunch kit that forms no part of the claimed design.

1 Claim, 7 Drawing Sheets(56)
